UNITED STATES PATENT OFFICE.

MAURICE JACOBS, OF TUCSON, ARIZONA.

SPARK PLUG.

Application filed March 2, 1926. Serial No. 91,763.

The invention relates to improvements in spark plugs for internal combustion engines, and it is my object to provide a new and improved plug construction, in which novel provision is made, permitting the electrodes to be removed when they are badly worn, and allowing new electrodes to be readily substituted.

With the foregoing in view, the invention resides in the novel subject matter herein-after described and claimed, the description being supplemented by the accompanying drawing.

Fig. 1 is a side elevation of a spark plug constructed in accordance with my invention.

Fig. 2 is an enlarged longitudinal sectional view on the correspondingly numbered line of Fig. 1.

Fig. 3 is a horizontal section on line 3—3 of Figs. 1 and 2.

While the drawing above briefly described, illustrates one advantageous construction, and this construction will be herein specifically described, it is to be understood at the outset, that within the scope of the invention as claimed, numerous variations may be made.

The numeral 4 designates a shell body having the usual flat-sided portion 5 for engagement with a wrench, and cylindrical, externally threaded portions 6 and 7 projecting in opposite directions from said portion 5, the portion 6 being adapted for reception in the usual spark plug opening of a cylinder head, while the portion 7 is received within a continuous shell cap 8. The shell body 4 and the cap 8 are so shaped as to effectively secure an insulator 9 in place, the usual gaskets 10 being employed.

The shell body 4 is divided on lines 11 extending longitudinally thereof, into two co-operable sections 12, which sections are held together by the shell cap 8 and by the cylinder head, when the spark plug is threaded into the latter. To assist in assembly, the sections 12 may be provided with any desired positioning means, such as interfitting tongues and grooves 13—14.

A grounded electrode 15 is provided, having an attaching portion 16 which is tightly held between the sections 12, but is readily removable when these sections are separated from each other by unthreading the plug from the cylinder head and removing the shell cap 8. The attaching portion 16 is shown in the form of a wedge-shaped head,

and opposed surfaces of the sections 12 are formed with angular notches 17 snugly receiving said head. These notches open through the inner end of the shell portion 6, through the exterior of this portion and through the interior thereof, in the present disclosure. Hence, the shell and the attaching portion 16 are provided with co-operative means to hold said portion 16 against movement toward either the exterior or the interior of the shell. These co-acting means may well consist of studs 18 on the attaching portion 16, and sockets 19 in the shell sections 12, said sockets receiving said studs.

Preferably, the free edge of the shell portion 7 is formed with notches 20 at the ends of the lines 11, facilitating the insertion of a knife blade or the like to separate the shell sections 12, if they have become stuck together by carbon or the like, after a long period of use.

A metallic member is embedded longitudinally in the insulator 9 and embodies a tubular inner portion 21, an outer portion 22 extending to the outer end of the insulator and constituting a binding post, and an enlargement 23 within the portion of the insulator surrounded by the heavy intermediate portion 5 of the shell body 4, the three portions 21, 22 and 23 being preferably integral with each other as shown.

The tubular portion 21 extends to the inner end of the insulator 9 and is gradually increased in diameter toward said end. A central electrode 24 is snugly received in this tubular portion 21, being longitudinally tapered both for tight wedging engagement with said tubular portion, and to provide the electrode with an enlarged portion which projects beyond the insulator and is provided with flat surfaces 25 to be engaged by a wrench or other suitable tool. Screw-threads 26 are provided for connecting the smaller end of the electrode 24, with the portion 23 of the metallic member 21—22—23. By using a wrench or the like upon the flat faced portion of this electrode, it may be tightly threaded and wedged into operative position so that there is no danger of it becoming accidentally detached. Whenever the sparking point 27 of this electrode has become so worn as to be inefficient, the portions 25 may be engaged with a wrench or the like and the entire electrode removed. Then, a new electrode may be substituted.

As the wear on both electrodes 24—15 is

uniform, both of them should be renewed at the same time, but this may not in all instances be necessary.

It will be seen from the foregoing that I have provided a new and improved spark plug construction in which the majority of parts may be used throughout the life of the machine on which it is employed, unless breakage of the insulator 9 should accidentally occur. The electrodes however, may be renewed from time to time and after such renewal, the plug is just as efficient as a new plug.

Attention is again invited to the fact that within the scope of the invention as claimed, various modifications may be made.

I claim the following as newly invented with respect to spark plugs:—

1. A spark plug comprising a shell externally threaded for engagement with the usual spark plug opening of a cylinder head, said shell embodying relatively separable sections having edges abutting on lines crossing the screw threads, whereby said sections will be held together when the plug is threaded into the opening, an insulator removably held between said sections and carrying an electrode, and an additional electrode free of connection with said insulator and having an attaching portion rigidly held

between said abutting edges of said sections, said additional electrode being removable upon separation of said sections.

2. A spark plug comprising a shell body externally threaded for engagement with the usual spark plug opening of a cylinder head, said body being divided into sections meeting on lines crossing the screw threads, an insulator removably held between said sections and carrying an electrode, a shell cap threaded upon the outer end of the shell body and holding said sections against separation prior to threading of the plug into the opening, and an additional electrode free of connection with said insulator and having an attaching portion rigidly held between said shell sections, said additional electrode being removable upon separation of said sections after removal of said cap.

3. A structure as specified in claim 1; said attaching portion of the electrode being in the form of an enlarged head, said abutting edges of said shell sections being recessed from the interior to the exterior of the shell to receive said head, said head and shell having co-acting means to prevent movement of said head toward the interior or exterior of the shell while the shell sections remain assembled.

MAURICE JACOBS.
